UNITED STATES PATENT OFFICE.

ALBERT O. BUCKIUS, JR., OF CLEVELAND, OHIO, ASSIGNOR, BY MESNE ASSIGNMENTS, TO NATIONAL MALLEABLE AND STEEL CASTINGS COMPANY, OF CLEVELAND, OHIO, A CORPORATION OF OHIO.

JOURNAL-BOX MECHANISM.

Application filed April 17, 1923, Serial No. 632,606. Renewed November 15, 1924.

Fig. 1 is a section of a journal box embodying my invention with the lid in closed position; and Figs. 2, 3 and 4 are sections similar to Fig. 1 showing the lid in half 5 opened position, not quite full opened position, and full opened position, respectively.

My invention relates to journal boxes of the type shown in my prior Patent No. 1,099,964, granted June 16, 1914, and comprises an improved structure in which the lid mechanism has been made to conform to and operate with the A. R. A. standard hinge lug without loss in effectiveness. To this end I employ a lever, which, when the 15 lid is in closed position, has a bearing lying wholly within the mouth of the box, and the lid and hinge lug are arranged so as to provide a flat and uninterrupted seating bearing for the lid clear around the edges 20 of the mouth of the box. My invention also comprises the various features which I shall hereinafter describe and claim.

Referring to the drawings, 2 represents the journal box having a hinge lug 3 of 25 standard A. R. A. design, to which the lid 4 is secured by the hinge pin 5. On the inside of the lid 4 is a bearing 6 for a coil spring 7, the upper end of which bears against the lower arm 8 of the bell crank 30 lever 9. The lever 9 preferably has integral trunnions 10 which seat in the sockets 11 on the inside of the lid. The upper arm of the lever has, beginning at its upper point 12, a convex face 13 which merges into the 35 elongated concave face 14, both of which in different operative positions of the lid 4 and lever 9 come into bearing against the downward projection 15 of the hinge lug 3, which lies flush with or within the mouth of the 40 box. The lower portion 16 of the forward face of the hinge lug 3 is preferably slightly concave and is usually provided with a recess or notch 17 therein. The surface 16 also forms a part of a flat and uninterrupted 45 seating bearing for the lid clear around the edges of the mouth of the box.

When the lid is closed, as is shown in 50 Fig. 1, the bell crank lever 9 bears near the lower end of its concave face 14 against the inner side of the projection 15 of the hinge lug 3, and the pressure exerted against the lower arm 8 of the lever by the spring 7 serves to hold the lid tightly against the mouth of the box. As the lid is opened from

the position shown in Fig. 1 to that of Fig. 55 2, in which the spring 7 occupies a position of nearly maximum compression, the lever 9 slides about the projection 15 until the convex portion 13 of the upper end 60 12 of the lever wipes around the projection 15 and reaches the forward face 16 of the hinge lug 3, and the spring 7 is then free to expand and force the lever 9 to throw the lid 4 to full opened position shown in Fig. 4, in which the upper edge 18 of the 65 lid (which is in the form of a housing) has come into contact with the shoulder 19, which is to the rear of the top side of the hinge lug 3.

In closing the lid, pressure is applied at 70 the outer edge of the lid, the lever 9 being in the position shown in Fig. 4, with the point 12 of the lever tilted away from the recess 17 in the forward face 16 of the hinge lug 3, the face 13 of the lever 9 being convex so as to prevent the point 12 from becoming lodged in the recess and thereby rendering the device inoperative. As is shown in Fig. 3, the point 12 of the lever 75 rides over the recess 17 and engages that 80 part of the lug face 16 which lies below the recess 17. Continued closing pressure on the outer edge of the lid brings the point 12 of the lever around the point of projection 15, when the spring 7 is free to expand and 85 snap the lid shut. When the lid 4 is in closed position, as is shown in Fig. 1, the upper end of the lever extends up into the recess 20.

As is indicated in Fig. 1, the spring holds 90 the lever so close to the lid that neither lever nor spring can be detached from the lid unless the spring is compressed and the lever rotated so as to disengage the trunnions 10 from the sockets 11 on the lid. This permits the lid to be shipped with the parts 95 assembled thereon without it being necessary to secure the parts thereto.

To provide sufficient leverage for the lid and also to prevent interference with the 100 journal box wedge 21, the thickness of the upper end of the lever 9 is decreased, and its working face lengthened by making it concave at 14 to give a more extended bearing on the projection 15. As a result, the 105 upper point 12 of the lever at the beginning of the opening (or near the end of the closing) movement swings through a

parabolic arc, as is indicated in dotted lines in Fig. 1, and hence safely clears the journal box wedge 21 in spite of the extreme length of the working face of the lever.

5 Not only is my improved mechanism one which preserves all the advantages of the lids of the type of my Patent 1,099,964 which are now in use and enables the lids to be used with boxes embodying the A. R. A. standard, 10 but it also provides a lid which may be shipped with all the parts assembled ready to be applied to journal boxes.

The terms and expressions which I have employed are used as terms of description 15 and not of limitation, and I have no intention, in the use of such terms and expressions, of excluding any mechanical equivalents of the features shown and described, or portions thereof, but recognize that various 20 structural modifications are possible within the scope of the invention claimed.

What I claim is:

1. In journal box lid mechanism, the combination with a journal box characterized 25 by a mouth opening and a hinge lug, the mouth opening having an uninterrupted flat surface thereabout arranged in a single plane, which said surface merges into the lower portion of the hinge lug, and in these respects identically corresponding to a journal box of standard American Railway Association type; a lid pivoted to the hinge lug; the hinge lug having within the box a recess partially overlying a journal box wedge; operating mechanism between the lid and the hinge lug comprising a spring 30 pressed lever; the upper end of the said lever having an operating face engaging a downward projection on the hinge lug, the extent of said face inside the point of engagement with the projection when the lid is closed being greater than the distance from 35 said point to the journal box wedge, the operating face of the lever being recessed to permit the upper end of the lever to move 40 about said point during the opening and closing of the lid in substantially a parabolic path to prevent contact with said journal box wedge.

50 2. In journal box lid mechanism, the combination with a journal box characterized by a mouth opening and a hinge lug, the mouth opening having an uninterrupted flat surface thereabout arranged in a single plane, 55 which said surface merges into the lower portion of the hinge lug, the upper portion of the face of the hinge lug and the lower portion being separated by a recess, and in

these respects identically corresponding to a journal box of standard American Railway Association type; a lid pivoted to the hinge lug; a spring pressed lever having its operating face terminating in a rocker, the lever being arranged during the opening and closing movements of said lid to move along the said face of the hinge lug and across the said recess upon its rocker, said rocker being of an extent and curvature sufficient to span said recess and prevent the end of the lever from wedging therein, the said lever also engaging a portion of said box inward of the plane of said mouth opening to hold the lid in closed position.

3. A hinged lid for journal boxes, comprising a lever pivoted in open sockets on the inside of the lid, a spring between one arm of the lever and the lid, the other arm of the lever normally extending substantially parallel to the lid and close to a portion thereof, the said lever having a spring 80 pressed bearing on the inside of the lid to prevent accidental separation therefrom before application to the box and being incapable of separation from the lid except by rotation in said sockets and upon strong 85 compression of said spring, said lever engaging also a portion of the box inside the mouth of the box when the lid is applied to the box.

4. In journal box lid mechanism, the combination of a journal box of standard American Railway Association type, characterized by a mouth opening and a hinge lug, the lower portion of the front face of said hinge lug merging into a plane surface about the 90 said mouth opening, said plane surface forming a continuous and uninterrupted flat bearing face about said mouth opening; a lid pivoted to the hinge lug having a continuous flat bearing upon the said face when the 100 lid is closed whereby the entire mouth opening is sealed by the lid; the middle portion of the lid extending outwardly from the plane of the mouth opening; the walls of such portion sloping inwardly at all points 105 into the said continuous bearing surface of the lid; and a spring actuated lever mounted in the said middle portion of the lid and extending inwardly therefrom, said lever bearing on a portion of the hinge lug within 110 the mouth of the box when the lid is closed and being adapted to travel across a portion of the said plane surface during opening and closing movements of the lid.

ALBERT O. BUCKIUS, JR.
